AUXILIARY STOP LIGHT FOR AUTOMOBILES OR THE LIKE

Wilbur G. Neuenschwander, 120 N. Main St.,
Bluffton, Ohio

Filed Oct. 17, 1960, Ser. No. 62,498

Term of patent 14 years

(Cl. D48—32)

FIGURE 1 is a perspective view of an auxiliary stop light for automobiles or the like, showing my new design;
FIGURE 2 is a front elevation thereof;

FIGURE 3 is a rear elevation thereof;

FIGURE 4 is a side elevation thereof as seen from the right of FIGURE 3;

FIGURE 5 is a side elevation thereof as seen from the left of FIGURE 3;

FIGURE 6 is a top plan view thereof;

FIGURE 7 is an enlarged fragmentary perspective view thereof.

I claim:

The ornamental design for an auxiliary stop light for automobiles or the like, substantially as shown.
